UNITED STATES PATENT OFFICE.

JAMES RUSSELL TISDALE, OF VANCOUVER, BRITISH COLUMBIA, CANADA.

DESIGN FOR A DISPLAY CASE.

Application filed June 23, 1927. Serial No. 22,532. Term of patent 7 years.

To all whom it may concern:

Be it known that I, JAMES RUSSELL TISDALE, a resident of the city of Vancouver, in the Province of British Columbia, Canada, have invented a new, original, and ornamental Design for a Display Case, of which the following is a specification, reference being had to the accompanying drawing, forming part thereof.

The figure represents a perspective view of my display case.

I claim:

The ornamental design for a display case as shown.

JAMES RUSSELL TISDALE.
